UNITED STATES PATENT OFFICE.

JAMES F. KELLY, OF GALENA, ILLINOIS.

RAIL-CLAMP.

SPECIFICATION forming part of Letters Patent No. 770,861, dated September 27, 1904.

Application filed January 28, 1904. Serial No. 191,039. (No model.)

To all whom it may concern:

Be it known that I, JAMES F. KELLY, a resident of Galena, in the county of Jo Daviess and State of Illinois, have invented certain new and useful Improvements in Rail-Clamps; and I do hereby declare the following to be a full, clear, and exact description of the invention, such as will enable others skilled in the art to which it appertains to make and use the same.

10 My invention relates to an improved rail-clamp, the object of the invention being to provide improvements of this character in which ordinary railroad-rails are secured by my improved clamp, which compels or permits ordinary spikes to be driven at an angle or incline and in opposite directions, thereby increasing their effectiveness.

With this object in view the invention consists in certain novel features of construction and combinations and arrangements of parts, as will be more fully hereinafter described, and pointed out in the claims.

In the accompanying drawings, Figure 1 is a view in side elevation illustrating my improvements. Fig. 2 is a top plan view, and Fig. 3 is a view in cross-section.

15 1 represents a railroad-rail of ordinary construction supported on ties 2 and secured thereon by my improved clamping-plates 3. These plates 3 each comprise a metal bar, adapted to rest on the rail-base flange 4 and having depending flanges 5 at their outer edge to be located against the outer edge of the base-flange and seat the clamping-plate in proper position, it being understood that similar clamping-plates are located at opposite sides of the rail. The shape of the clamping plate or plates is shown clearly in Fig. 1, each plate having an intermediate flat portion 6 inclining upward at its ends, as shown at 9, to receive the heads 7 of ordinary spikes 8 and having upwardly-projecting lugs 10 at the ends to prevent the spike-heads passing over the same or the plate from moving from under the heads.

20 In operation the plates 3 are placed on the base-flange 4 and spikes 8 driven into the ties in opposite directions at an angle of twenty degrees, more or less, to locate the

heads 7 properly over the inclined faces 9 and securely clamp the plate on the rail and the latter on the tie.

25 A great many slight changes might be made in the general form and arrangement of the parts described without departing from my invention, and hence I do not restrict myself to the precise details set forth, but consider myself at liberty to make such slight changes and alterations as fairly fall within the spirit and scope of my invention.

30 Having fully described my invention, what I claim as new, and desire to secure by Letters Patent, is—

35 1. A rail-clamp, constructed to lie upon a flange of a rail and having two oppositely-inclined faces to receive the heads of spikes driven at an angle into the tie alongside the flange of a rail.

40 2. A rail-clamp, comprising a plate constructed to lie upon a flange of a rail and having oppositely-inclined faces at its ends, to receive the heads of spikes driven at an angle into the tie and in opposite directions alongside the flange of a rail.

45 3. A rail-clamp, comprising a plate adapted to fit against the base-flange of a rail and having upwardly-inclined end portions to receive the heads of spikes driven into the tie at an angle in opposite directions.

50 4. A rail-clamp comprising a bar constructed to rest upon a flange of a rail at or near the edge of the latter, said bar having faces near its respective ends, inclined toward the center of the plate and toward the outer edge of the plate.

55 5. The combination with a rail, of clamping-plates on opposite sides of the rail, located against the base of the rail and having upwardly-inclined ends, and spikes driven at an angle into the tie and having their heads engaging the inclined ends of the plates.

60 In testimony whereof I have signed this specification in the presence of two subscribing witnesses.

JAMES F. KELLY.
